GRAIN DRIER

William W. Jakubik, Rosenberg, Tex.

Application August 4, 1947, Serial No. 765,945

1 Claim. (Cl. 34—164)

1 This invention relates to grain drying apparatus and particularly concerns a grain drier of the type having a drying tower through which grain descends and is subjected to heated air.

In grain driers of this type, the grain is usually constantly moved by gravity over a series of inclined trays and, at the same time, subjected to an upward blast of heated air. Some improvement in the gravity type of conveyer has been accomplished by agitating the trays. Generally, this agitation is effected by reciprocating the trays. However, whether or not the trays are agitated, it is necessary to incline them rather steeply in order to avoid clogging.

With such steep slopes, only a few trays can be arranged in a tower of convenient height, and the speed at which the grain descends cannot be controlled. Even though the trays are inclined in opposite directions, the steep slopes necessary to avoid clogging causes the grain to descend very rapidly. In order to accomplish substantial drying in the short time that is required for the grain to descend to the bottom of such a tower it has been necessary to employ air of a very high temperature. As a result, the grain is heated to a high temperature but not completely dried. To reduce the temperature of the grain before passing it through another drying tower, it is usually necessary to make use of an intermediate cooling tower.

It is a major object of this invention to overcome the difficulties of previous grain driers by providing improved agitation for the inclined trays so the speed of the grain may be controlled to descend more slowly without the danger of clogging the tower.

Another object of the invention is to provide a grain drying tower which may employ drying air of a lower temperature and still completely dry the grain in one tower of convenient height.

A further object of the invention is to provide a grain drying system which may be set up on a farm to dry green grain. This is particularly useful in damp climates where the grain must be harvested before it is completely ripe, otherwise it will ruin in the field.

A still further object of the invention is to provide a single grain tower wherein the trays may be inclined less sharply without danger of clogging, thereby enabling a greater number of trays to be placed in a tower of convenient height.

A more particular object of the invention is to provide an apparatus in a grain drying tower for simultaneously reciprocating and oscillating inclined trays in the tower.

2 Another particular object of the invention is to provide an air control in the grain cooling tower whereby the grain coming into the top of the tower is not mixed with the air and trash moving upwardly through the tower.

Other objects and advantages of the invention will become apparent from the following specification taken in connection with the accompanying drawings wherein

10 Figure 1 is a schematic representation of a grain drier embodying the invention but having some parts removed for purposes of clearance;

15 Fig. 2 is a partial section taken on the line 2—2 of Fig. 1; and

20 Fig. 3 is a fragmentary top view, on an enlarged scale, of one of the trays incorporated in the grain drier.

25 According to the invention in its preferred form, the grain drying apparatus includes a heated air type grain drying tower having an opening at its top through which grain is discharged by an endless conveyer. A fan and heater are connected to the bottom of the tower to force heated air upwardly through the tower. A series of perforated trays are arranged one above another in the tower and are alternately inclined in opposite directions to provide a tortuous path for descending grain while permitting direct upward flow of heated air.

30 Each of these trays is supported for combined oscillating and reciprocating movements. Power driven devices operate to simultaneously oscillate and reciprocate the trays. This combined oscillating and reciprocating motion gradually moves the grain downwardly along each tray without danger of clogging the trays or stopping the downward flow of grain. By using this motion, the trays may be inclined at smaller angles to the horizontal so more trays can be arranged in a tower of convenient height. This, in effect, provides a longer drying path for the grain.

35 **40** **45** Grain discharged from the lower end of the drying tower is elevated by another endless conveyer to the upper end of a cooling tower. A fan is provided to force cool air upwardly through the cooling tower. An air valve in the top of the cooling tower divides the opening therein into an entrance for dried grain and an exit for cool air. This valve is adjustable to vary the ratio of the areas of the two openings.

Referring now to the drawings, the grain drying tower 11 is supported on a pedestal 12 arranged on a suitable base 13. The grain drying tower is preferably square or rectangular in cross-section having straight sides 14, 15, 16 and

17. An air pump 18 driven from a motor 19 may be heated as by a suitable burner 21 supplied with fuel through a pipe 22. This heated air passes through duct 23 into the lower end of the drying tower 11. The air may escape from the tower 11 through a conventional stack 24.

18. Grain to be dried is placed in a hopper 25 and flows by gravity down chute 26 to an endless bucket conveyer 27 which may be enclosed within a casing 28. The conveyer 27 may also be driven from the motor 19 as by a belt 29 and pulley 31. The grain to be dried is carried upwardly by buckets 32 on the conveyer and discharged into an entrance 33 formed near the top of the drying tower.

19. In order to control the rate of descent of the grain to the bottom of the drying tower 11, a tray 34 is supported within the tower and angularly inclined with respect to the horizontal. Directly below the tray 34 a similar tray 35 is inclined in the opposite direction. As shown in the drawings, several additional trays 36, 36, may be arranged one above the other within the tower and alternately inclined in opposite directions. Each of the trays is provided with upwardly turned sides 38 and 39, and also has its upper end turned up as at 41. With the trays angularly inclined in opposite directions, they form a tortuous path along which the grain flows. In order that the heated air may pass directly from the bottom to the top of the tower and also pass through the grain to be dried, each of the trays has a perforated bottom, as indicated at 42, 42. The perforations should be small enough to prevent grain from falling through the openings but large enough to permit free passage of air.

20. Each of the trays is mounted in the tower for combined reciprocating and oscillating motions. As shown most clearly in Fig. 2, the tray 34 has its lower end pivotally connected as by stub shafts 43 and 44 to links 45 and 46. The link 45 is pivotally connected to the sides 16 of the tower as by a stub shaft 47 which is journaled in a bearing 48. Similarly, the link 46 is supported on a stub shaft 49 journaled in bearing 51 on the side 17 of the tower. With this arrangement, the lower end of the tray 34 is pivotally connected to links 45 and 46 which are mounted in the tower to turn about the axis of shafts 47 and 49 above the lower end portion of the tray.

21. The upper end portion of each of the trays is supported so it may be oscillated about an axis below its respective upper end portion. This is shown most clearly in Fig. 2 in connection with the tray 35. The upper end portion of the tray 35 is pivotally connected to a pair of links 53 and 54, which are longer than links 45 and 46, as by a bolt 55 in a clevis 57 and a bolt 56 in a clevis 58 mounted on the bottom of the tray. The lower ends of the links 53 and 54 are fixed, as by welding indicated at 61, to a shaft 62 journaled in bearings 63 and 64 mounted on the sides 16 and 17, respectively, of the tower. Thus, the upper ends of the trays are pivoted to links which turn about axes arranged below their respective upper ends. As links 45 and 46 are shorter than links 53 and 54, the upper ends of the trays turn on a longer radius than the radius on which turn the lower ends of the trays.

22. In order to oscillate and reciprocate the trays, the shafts 62 are simultaneously oscillated. For this purpose, a crank pin 64 eccentrically mounted on a wheel 65 is connected to a vertically disposed rod 66. Vertical movements of the rod 66 are transmitted through a sliding connection, il-

23. lustrated by pins 67 and 68, to cranks 69 on each of the shafts 62. Inasmuch as the shafts 62 are alternately arranged on opposite sides of the rod 66, the shafts will be rotated in opposite directions for alternate trays. The wheel 65 may be driven through a belt 71 from the motor 19.

24. From this description it will be apparent that the upper ends of each of the trays oscillates about the axis of its respective shaft 62 arranged below said upper end while the lower ends of the trays are oscillated on a shorter radius about axes above said lower ends. The two ends of the trays are, therefore, simultaneously moved along oppositely disposed arcs. This effectively causes reciprocation of the trays in the direction of their inclination and, at the same time, causes oscillation of the trays about a transverse axis midway between the ends. Due to the differences in the radii of the arcs about which the upper and lower ends of the tray move, the lower ends move a greater distance in a vertical direction and a shorter distance in a horizontal direction, thereby improving the agitation of grain on the trays.

25. The oscillation of the tray keeps the grain moving away from the surface of the tray so it is at all times completely subjected to the drying action of air passing upwardly through perforations in the bottom of the tray. Also, oscillation of the trays prevents the grain from sticking to them. The reciprocating motion of the trays causes the grain to move in the direction of its inclination. The trays may be inclined at relatively small angles with respect to the horizontal so downward movement of the grain is comparatively slow, because the danger of clogging is eliminated by the combined oscillating and reciprocating motion of the trays. By this expedient, a greater number of trays may be placed within a tower of convenient height and thereby the path of descending grain is elongated without increasing the height of the tower.

26. Since the path of the grain is longer, and the rate of flow of the grain is slower, the grain is subjected to heated air for a greatly increased period of time. This enables the grain to be completely dried in one tower without subjecting it to excessive temperatures. When the grain reaches the bottom of the tower 11, it moves along a chute 71 to a second endless bucket conveyer 72 which may be enclosed within a casing 73. Buckets 74 elevate the grain from the bottom of the drying tower to the top of a cooling tower 74 which has an opening 75 in its upper end.

27. This opening is divided by an air valve 76 so grain discharged from the buckets 74 moves over a baffle 77 down a chute 78 and through an entrance on one side of the valve 76. The other side of the valve 76 cooperates with a passage 79 to form an exit for cool air which is forced upwardly through the cooling tower 74 by a fan 81. The fan 81 may be driven by a belt 82 from the motor 19. A series of oppositely inclined chutes 83, 83, are arranged within cooling tower 74 to provide a tortuous path for descending grain. When the grain reaches the bottom of the cooling tower it flows through a sacker 85 provided with a valve 86 for supplying the grain first through one chute 87 and then through another chute 88 into sacks disposed below the cooling tower.

28. A particular feature of the cooling tower embodying the invention is the air controlled valve 76 which may be adjusted as by a handle 89 to vary the ratio of the entrance and exit openings. 75. This valve is preferably adjusted so only grain

will pass through the entrance, and all air, together with any trash carried by it, will pass outwardly through the exit and passage 79.

In operation, grain placed in the hopper 25 is elevated by the endless conveyer 27 to the entrance 33 in the upper end of the drying tower 11. It then passes on to the alternately inclined perforated trays 34 and 35, which are arranged to simultaneously oscillate and reciprocate as described above. The speed of descent of the grain through the drying tower may be controlled by the speed at which the wheel 65 is driven to cause agitating movement of the trays. When the grain reaches the bottom of the drying tower it is elevated by endless conveyer 72 to the upper end of the cooling tower 74. It is cooled as it descends to the bottom of the cooling tower and is ready to be placed in sacks upon discharge through the sacker 85.

What is claimed is:

In a grain drying tower, grain agitating means comprising a series of perforated trays arranged one above the other within said tower and alternately inclined in opposite directions, each of said trays having its lower end portion pivotally connected to the lower end of a pair of transversely spaced links, the upper end of each link

being pivotally mounted in the tower to turn about a transverse axis, the upper end portion of each of said trays being pivotally connected to links fixed to transverse shafts journaled in the tower below each of said upper end portions, the links connected to the upper portions of the trays being longer than the links connected to the lower portions of the trays, and means for oscillating said shafts to longitudinally reciprocate and simultaneously oscillate each of said trays about a transverse axis.
